UNITED STATES PATENT OFFICE.

OTTO C. FOSSELMAN, OF CHICAGO, ILLINOIS.

COUNTERBALANCED DOOR.

1,012,834.

Specification of Letters Patent. Patented Dec. 26, 1911.

Application filed March 3, 1909. Serial No. 481,189.

To all whom it may concern:

Be it known that I, OTTO C. FOSSELMAN, a citizen of the United States, residing at Chicago, in the county of Cook and State of Illinois, have invented a certain new and Improved Counterbalanced Door, of which the following is a full, clear, concise, and exact description, reference being had to the accompanying drawings, forming a part of this specification.

My invention relates to counterbalanced doors, with special reference to a form of door which will be readily and quickly operated.

I am aware that counterbalanced doors have been used in the past, but the chief objection to all previous forms has been the slowness and difficulty of operation. It has been usual to support a counterweight to a chain which has been operated over a pulley, the chain being suitably attached to the door. In my improved form of door a counterbalancing weight is directly attached by means of a suitable framework to the door itself, the door being raised by being swung outwardly or inwardly, as the case may be, to form a canopy. The door being hinged at its upper part, it is evident that the door and its attached counterbalance act as a lever pivoted to the under side of the lintel.

In the preferred form of my invention the door is made in upper and lower portions, the two portions being suitably hinged together. When the door is raised the two portions become folded together, the lower half of the door being retained in its proper position by means of wheels which run in suitable guides. By using a door which is thus divided into an upper and lower portion, it is possible to use a much lighter counterweight than can be used when the door is made in the form of a single piece.

Turning now to a detailed description of my invention—Figure 1 is a rear elevation of the door with its surrounding framework; Fig. 2 is a partial front elevation of the door; Fig. 3 is a sectional view on the plane 3—3 of Fig. 2; Fig. 4 is a vertical section of a door consisting of a single piece on a plane similar to that of Fig. 3; Fig. 5 is a vertical section of a modified form of door on a plane similar to that of Fig. 3; Fig. 6 is an enlarged section taken

on the plane 6—6 of Fig. 1; Fig. 7 is a front elevation of a modified form of the guiding mechanism for the door; and Fig. 8 is a section on the line 8—8 of Fig. 7.

In Fig. 1 the door is made up of the upper portion 1 and the lower portion 2. To the upper portion 1 are attached the supports 3, 3, 3, to which is attached the counterbalancing weight 4. The upper and lower portions of the door are suitably joined by the hinges 5, 5, 5. Attached to the frame of the door are angle irons 6, 6 which, in connection with angle irons 7, best shown in Fig. 6, form suitable guides or tracks in which the wheels 9, 9 attached to the bottom of the lower portion 2 of the door are adapted to operate. The wheels 9 operate on an axle 10, which in turn is held in position by the plate 11. When the door is in its closed position two spring bolts 12, 12, which operate in the frames 12^a, 12^a rigidly fasten the door. The bolts 12, 12 are connected together by means of a suitable chain or rope 13. When it is desired to open or raise the door, the two bolts 12, 12 are released from their engaging position by pulling on the chain 13. The counterbalancing weight 4 then becomes effective and the lower portion of the door, having the wheels 9, 9 running in their guides, is made to occupy the position shown in dotted lines in Fig. 3, the upper portion of the door meanwhile coming into a position above and approximately parallel to the lower portion, this upper portion 1 being pivoted by means of the hinges 14, 14. The track 7 at its upper portion is a little inclined from a vertical position, as shown between the points 15 and 16, in order to allow the wheels 9, 9 to move slightly in an opposite direction from the counterweight and thus cause the two portions of the door to lie approximately in a horizontal plane when they are in a raised position. The closing of the door is accomplished by means of a rope or chain 17 attached to the frame of the door at 18 and to the door by means of the eye 19. When the door is raised it can thus easily be closed by pulling on the rope 17 until the lower portion is nearly in its normal position, and then by exerting suitable pressure near the point where the two portions of the door are joined by hinges the door is completely closed.

In order to securely hold the door in its raised position I use the spring 42 which is attached to the frame of the door by the screw 43. When the door is raised this 5 spring is flattened against the bottom of the guide until the door has passed it. It is then released and acts as a supporting means for the door itself. When the door is again closed the spring is similarly flattened by 10 having its free end extend in an upward direction and it again assumes its normal position after the door has passed it. I also provide auxiliary means by which the door will automatically be closed in case of fire. 15 To the lintel of the door is attached a framework 20 within which is supported the spring 21. The portion 22 of this spring cooperates with the bar 23 which is shown in its normal position in dotted lines in Fig. 3. 20 At its outer end the bar 23 is normally supported to the beam 24^a by eye bolt 24, a cord 25 and link 26 of readily fusible material which is inserted in the opening 27 of the bar 23. If the door is in its raised position and there should be a fire the link 26 25 would become melted or the cord 25 would be burned. When this happens the bar 23 would be released and by the operation of the spring 21 would force the door to its closed position and occupy the position shown in full lines in Figs. 2 and 3. As a further protection against fire I provide a 30 plate 40 shown in Fig. 1. The thickness of the door has been considerably reduced where this plate is placed and is cut down 35 to a minimum at the portion immediately behind the depressed portion 41 of the plate. In case of fire it is a matter of but little difficulty to break through the door by exerting suitable pressure on the portion 41, and 40 when an opening has been made at this point the bolts 12, 12 can easily be withdrawn by pulling on the chain 13 and the door thus readily opened.

45 A modification of the door is shown in Fig. 4, where instead of being made in two portions, the door itself consists of a single portion 28 which is suitably braced by brace 29 and the T-rail 30 which are suitably attached to the door by the brackets 31, 32 and 33. When this style of door is opened it is evident that the whole structure swings 50 on the pivot 34 of the hinge 35, and the door occupies the position partially shown in dotted lines. This style of doorway is particularly useful where it is desirable to obtain 55 the protection of a canopy.

60 A further modification of the door is shown in Fig. 5, where the structure is particularly adapted to be used in connection with elevators. In place of having the counterweight outside of the door frame, in this modification it occupies the inside 65 and the door itself in its raised position is outside of the door frame. The advantage

of this method of construction is that the counterweight operates within a very restricted radius outside of the door frame itself and is adapted to interfere but little with the operation of the elevator.

70 When the door is particularly wide or made of comparatively light material, it is clear that there might be a tendency for one side of the door, where the wheels are attached, to rise somewhat more rapidly than the other side. In order to obviate this I 75 use the modification shown in Fig. 7, where, in place of wheels, the pinions 36, 36 are used which are rigidly connected by the axle 37 which operates in the bearings 38. The 80 pinions 36, 36 are adapted to operate in connection with the racks 39, 39 which are placed on the opposite side of the guides from that on which the counterweight is placed. By this arrangement it is made impossible for one side of the door to rise at a 85 different rate from that of the other side.

90 As an additional means of providing protection in case of fire, in some cases I provide a chain 44 which is attached at or near the middle of chain 13 at the point 45. This chain 44 runs through an opening 46 in the section 2 of the door. On the side opposite to that on which the chain 13 is placed is provided a handle 47. It is evident that 95 by this means the door can be opened both from the front and rear; from the front by means of pulling directly on the chain 13, and from the rear by pulling on the handle 47.

100 Considerable modifications can be made from the exact structure which is described without departing from the underlying principle of my invention.

What I claim as new and desire to cover by Letters Patent is:

110 1. In a counterbalanced door structure, a door frame, a door within said frame, said door and said frame being in the same vertical plane said door horizontally divided into a plurality of sections, hinge means for joining said sections, means for supporting the upper section of said door from said frame, guideways associated with said frame, guiding means associated with said sections, said guiding means adapted to operate in said guideways, and a counterbalancing weight rigidly attached to the upper section of said door and in a different plane 115 from said door, said weight tending to swing said section from a vertical to a horizontal position and to drag the lower section upward with it.

120 2. In a counterbalanced door structure, a door frame, a door within said frame, said door and frame being normally in the same vertical plane, said door being horizontally divided into a plurality of sections, hinges for joining said sections, hinges for supporting the upper section of said door from 125 130

the lintel of said frame, vertical guideways associated with said frame, guiding means associated with the sides of said sections, said guiding means adapted to operate in 5 said guideways, a bracket attached to the upper section of said door, and a weight connected with said bracket, said weight and said door being in separate vertical planes, said weight tending to simultaneously swing said upper section from a vertical 10 to a horizontal position and to drag said lower section upward with it.

3. In a counterbalanced door structure, a door frame, a door within said frame, said 15 door and said frame being normally in the same vertical plane, said door being horizontally divided into two sections, hinge means for joining said sections, pivotal means for supporting the upper section 20 from said frame, vertical guideways associated with said frame, guiding means associated with the sides of the lower section, said guiding means adapted to operate in said guideways, and a counterbalancing 25 weight attached to said upper section, said weight being in a different vertical plane from said door and tending to simultaneously swing said upper section from a vertical 30 to a horizontal position and to drag said lower section upward with it.

4. In a counterbalanced door structure, a door frame, a door within said frame, said door being horizontally divided into an upper and a lower section, hinges for joining 35 said sections, hinges for supporting said upper section from the lintel of said frame, wheels associated with the sides of said lower section, guideways for said wheels associated with the sides of said frames, the 40 direction of said guideways at their upper parts being so modified that when said wheels are raised the axes of said wheels will be brought into the same vertical plane as the axes of said hinges supporting said 45 upper section, a bracket attached to said upper section, and a weight connected with said bracket, said weight tending simultaneously to swing said sections from a vertical 50 to a horizontal position and to raise said lower section toward the horizontal plane of said lintel.

5. In a counterbalanced door structure, a door frame, a door within said frame, said door being horizontally divided into an upper and a lower section, hinges for joining 55 said sections, hinges for supporting said upper section from the lintel of said frame, pinions associated with the sides of said lower section, racks associated with the sides 60 of said frames, said pinions adapted to cooperate with said racks, the direction of said racks at their upper parts being so modified that when said pinions are raised the axes of said pinions will be brought into the same 65 vertical plane as the axes of said hinges sup-

porting said upper section, a bracket attached to said upper section, and a weight rigidly secured to said bracket, said weight tending to simultaneously swing said sections from a vertical to a horizontal position and to raise said lower section toward the horizontal plane of said lintel. 70

6. In a counterbalanced door structure, a door frame, a door within said frame, said door being horizontally divided into an upper and a lower section, hinges for joining said sections, hinges for supporting said upper section from the lintel of said frame, vertical guideways associated with the sides of said frame, wheels associated with the sides of said lower section, said wheels adapted to operate in said guideways, a bracket attached to said upper section, a weight connected with said bracket, said weight tending simultaneously to swing 80 said sections from a vertical to a horizontal position and to raise said lower section toward the horizontal plane of said lintel, and resilient means associated with said guideways for retaining said sections when in 85 said horizontal and raised position, said sections being automatically disengaged from said retaining means. 90

7. In a counterbalanced door structure, a door frame, a door within said frame, said door being horizontally divided into an upper and a lower section, hinges for joining said sections, hinges for supporting said upper section from the lintel of said frame, vertical guideways associated with the sides of said frame, wheels associated with the sides of said lower section, said wheels adapted to operate in said guideways, a bracket attached to said upper section, a weight connected with said bracket, said weight tending simultaneously to swing 100 said sections from a vertical to a horizontal position and to raise said lower section toward the horizontal plane of said lintel, and a spring associated with said 105 guideways for retaining said wheels, thereby holding said sections when in their horizontal and raised position, said sections being automatically disengaged from said 110 spring. 115

8. In a counterbalanced door structure, a door frame, an upper door section hinged in said frame, a counterbalancing weight rigidly secured to the upper section, a lower section hinged to the bottom of said upper section, and means for vertically guiding the lower end of said lower section, said lower section merely hanging from said upper section and arranged to follow it in response to the action of said counterbalancing weight. 120

9. In a counterbalanced door structure, a door frame, a door within said frame, said door horizontally divided into a plurality of sections, hinge means for joining said 125 sections, hinge means for joining said 130

sections, means for suspending said door from said frame, said door and said frame being in the same vertical plane, and a counterbalancing weight rigidly attached 5 to said door, said weight adapted to swing said sections from vertical to horizontal positions.

10. In a counterbalanced door structure, a door frame, a door hinged to the lintel of 10 said frame, said door being horizontally divided into a plurality of sections, means for vertically guiding the lower end of the bottom section of said door, a bracket rigidly secured to the upper section of the door 15 and extending beyond the axis upon which it is hinged, and a weight rigidly secured to said bracket, said weight tending to swing said upper section into a horizontal position, said upper section drawing said lower

section with it so as to bring it also in a 20 horizontal position.

11. In a counterbalanced door structure, a door frame, an upper door section hinged to the top of said frame, a lower section hinged to the bottom of said upper section, 25 means for vertically guiding the lower edge of said lower section, and a weight rigidly secured to the upper section extending beyond the stationary hinge axis thereof to counterbalance the door to remove side 30 strains from the stationary hinge axis.

In witness whereof, I hereunto subscribe my name this 25th day of February, A. D. 1909.

OTTO C. FOSSELMAN.
